UNITED STATES PATENT OFFICE.

VICTOR WINQUIST, OF ROCKFORD, ILLINOIS, ASSIGNOR TO BURD HIGH COMPRESSION RING COMPANY, OF ROCKFORD, ILLINOIS, A CORPORATION OF ILLINOIS.

RING-GRINDING MACHINE.

1,402,700.

Specification of Letters Patent.

Patented Jan. 3, 1922.

Application filed February 10, 1920. Serial No. 357,736.

To all whom it may concern:

Be it known that I, VICTOR WINQUIST, a citizen of the United States, residing at Rockford, in the county of Winnebago and 5 State of Illinois, have invented certain new and useful Improvements in Ring-Grinding Machines, of which the following is a specification.

This invention relates in general to the 10 art of grinding and has more particular reference to mechanism operating in conjunction with a grinder for automatically feeding rings, washers, disks, or any articles having parallel sides, between a pair of abrasive disks for grinding said parallel sides. The article to be ground might be circular, polygonous, or of irregular contour, and in the 15 present illustration of my improvements the particular articles are piston rings.

One of the primary objects of this invention is to provide novel mechanism operating in conjunction with a grinding machine for grinding the sides of rings or similar articles most expeditiously, accurately and 20 economically.

Another object is the provision of mechanism which will automatically remove a ring from a magazine, feed it between a pair of abrasive disks, and then eject the ground ring preferably onto a receiving rack.

Still another object resides in the provision of mechanism of novel design peculiar to the conditions and requirements in grinding piston rings, whereby this work may be 35 performed with precision and at comparative low cost.

Other objects and attendant advantages relative to the principle and mode of operation and the automatic feeding mechanism 40 will be better appreciated by those familiar with this art upon reference to the following description, when considered in connection with the accompanying drawings, in which—

Figure 1, is a side elevation of a feeding mechanism embodying my improvements, in connection with part of a grinding machine;

Fig. 2, an end elevation of the feeding mechanism, taken substantially on the line 50 2—2 of Fig. 1;

Fig. 3, a fragmentary perspective view illustrating mainly the means which feeds the rings from the magazine;

Fig. 4, a perspective view of ring magazine;

Fig. 5, a vertical sectional view through the magazine, taken on the line 5—5 of Fig. 1;

Fig. 6, a fragmentary perspective view showing chiefly the ring carrying means of 60 the jaws and co-operating parts, with the ring in position being ground;

Fig. 7, an edge view of the jaws;

Fig. 8, an end view of the cam which opens and closes the jaws;

Fig. 9, a fragmentary perspective view of that part of the mechanism which times the movement of the ring until it is picked up by the jaws, and which ejects the ring therefrom after the grinding operation; and

Fig. 10, a detail perspective of a cam and the bearing shown in Fig. 9.

Before entering into a detailed description of the mechanism which I have devised as an example for accomplishing the objects prefaced above, a brief statement will be given of the general cycle through which the rings pass.

The rings are fed one at a time from a magazine to what I term a loading station, 80 and during this operation another ring, gripped peripherally by a pair of jaws, is being carried edgewise between a pair of abrasive disks which grind the parallel sides of the ring. The jaws oscillate and thus 85 carry a ring into and out of the space between the grinding disks. In the movement of the jaws toward and from the disks they pass the loading station. When the jaws in the movement away from the disks pass beyond said station the ground ring will be ejected. During the movement of the jaws toward the disks the ring at the loading station will be entered between the jaws and carried thereby into the space between the 95 disk to be ground. Another ring will be automatically advanced to the loading station to be fed by the jaws after the ground ring has been ejected. The foregoing operation continues automatically.

Referring now to Figs. 1, 3, 4 and 5, it will be observed that a suitable frame 11 is provided and supports a magazine which may be in the form of vertical rods 12 spaced circumferentially about a tapered circular 105 opening 13 in a stationary part 14. A slide

15 is mounted to reciprocate horizontally immediately below said part 14, upon the surface 20. The stack of rings rests on the slide 15 when it is in its forward position shown in Fig. 3, and when the slide is retracted until the curved surface 16 reaches the point 17, the lowermost ring 18 will drop to the surface 15, in front of the slide. When the slide moves forward this ring 18 will be pushed along the slideway and delivered over the surface 19 into an incline chute defined in part by surface 21 and 22, Figs. 1 and 2 respectively, which guides the ring to a vertical position 23, which I have 15 termed a pre-loading position.

The slide may be operated by any suitable mechanism, but I prefer this shall include a safety means for preventing breakage of the mechanism in the event that the feed of a ring is blocked. The slide is reciprocated in the present instance from the shaft 24. This shaft carries an eccentric 25 for reciprocating a link 26 which oscillates a bell-crank lever 27 through the agency of links 28 and 29 and rod 31. The link 28 and rod 31 are connected to the link 29 by means of a ball and socket connection 32. The rod 31 is slidable through a part 33 on the link 26, and a spring 34 on said rod constantly urges 30 it upwardly to a position limited by the stop 35. A link 36 pivotally connects the slide 15 to the arm 37 of the bell-crank lever 27. From the foregoing it will be obvious that when the shaft 24 is revolved a one-half 35 revolution the lever 27 will be oscillated in a counterclockwise direction, viewing Fig. 3, thereby retracting the slide 15, and that the next one-half revolution of said shaft will cause the slide to feed a ring forward 40 in the manner described above. Should a ring jam in front of the slide, upward travel of the joint 32 will be stopped, and the rod 31 will move downwardly through the part 33 against the pressure of spring 34. This 45 action will be repeated until the machine is stopped and the jam displaced.

From the position 23, the ring moves to a loading station and thence between a pair of jaws, by means which will be described 50 hereinafter.

The jaws designated generally by characters 38 and 39 are relatively thin, of less thickness than a ring and are shaped to peripherally enclose the ring, as plainly shown. 55 In the present case the jaws are of sectional construction, but rigidly and detachably secured respectively to parts 41 and 42, the former of which is loose on shaft 43 and the latter fixed thereto. By removing the plates 60 44 the jaws 38 and 39 may be removed from the parts 41 and 42. The jaw 38 is constantly urged toward the jaw 39 by a spring 45 for the purpose of gripping or clamping an interposed ring, and a cam 46 carried by 65 part 41 is employed for separating the jaws.

This cam, rotatably supported by part 41, has a flat surface 47, Figs. 2 and 8, which bears against an adjustable stop 48 carried by part 42, and is adapted to be oscillated by means of rod 49 pivotally attached at 51 to 70 a stationary part and slidable at its outer end in an opening diametrically through the cam. The shaft 43 and consequently the jaws are oscillated to carry a ring into and out of grinding relation to the abrasive disks 75 (described hereinafter), by means of a crank disk 52 fixed to the shaft 43, which disk derives its movement from the link 26. Thus the ring feeding device and jaws are operated in timed relation. As shown in Figs. 2 80 and 6, the jaws have completed the said movement between the abrasive disks 53 and 54, and when the crank disk 52 is oscillated in a clockwise direction by downward movement of the link 26, the jaws will be likewise 85 moved and, before leaving the dotted line position shown in Fig. 2, caused to separate by action of the cam 46. The cam 46 is oscillated a number of degrees equal to the difference between the movement of the rod 90 49 and the jaw element 42, thus separating the jaws 38 and 39, as will be obvious. By adjustment of the screw 55, Fig. 2, the jaws may be accommodated to variations in ring diameters. 95

Attention is now directed more particularly to Figs. 1, 2 and 9. The ring in the position 23 rests on a timer shoe 56 secured to one end of a timer bar 57 which is supported by pendent links 58 to reciprocate 100 horizontally. The spring 59 normally holds the timer shoe 44 in a position between walls 61 and 62 which define the lower end of the chute mentioned above. When the shoe 56 is withdrawn by means presently to be described, the ring supported on said shoe will drop to and rest upon the inclined blocks 63, which position I term a loading station. The blocks are relatively adjustable to accommodate rings of different diameters. It 105 will be observed that the ring at this station is coincident with the path of the opening 64 in the jaws to permit such rings to enter said opening 64 through the opening 65 in the wall 61 when the jaws are swung past 110 the loading station in a counter-clockwise direction, as will be presently described. The timer rod 57, guided by the rollers 66 which are supported in boxes 67 having removable covers 68, is given a quick movement longitudinally for withdrawing the shoe 56. This is done at present by means of a lever 69 pivotally mounted at 71 on the frame and having an end 72 adapted to be actuated by an adjustable tappet 73 carried 115 by arm 37 of the bell-crank lever 27. The free end of the lever 69 operates between the faces 74 and 75 on the bar 57. This bar actuates, through the agency of chain connection 76, an ejector bar 77 pivotally mounted 120

125 65 130

at 78 and equipped with an ejector shoe 79 adjustable by reason of the slot connection 81. It will be noted that the spring 59 is attached also to the ejector bar and serves to 5 normally hold the latter in retracted position. The ejector will be given a vigorous movement at the time the jaws reach the dotted line position shown in Fig. 2 for the purpose of laterally ejecting the ground ring 10 from the jaw opening 64. The ejected ring may be caught by the rod 82 of a receiving rack of the kind described in application, Serial No. 357510, thus preventing breakage 15 of the rings and collecting them in orderly fashion. When the jaws are in their most retracted or ejecting position the jaw 39 covers about two-thirds of the opening 65 and constitutes a baffle or guide against which the ring at the loading station is 20 urged by pressure of the bar 57 and the timer head 56. This head is of channel shape, having a lower flange 83. Thus when the jaws move forward toward the abrasive disks the ring at the loading station 25 will be properly pressed into opening 64. Plate 84 limits outward movement of the ring, which will be instantly gripped by the jaws through the action of the cam 46.

After the ring has been entered between 30 the abrasive disks 53 and 54 which are revolved in opposite directions at a high speed, disk 54 will be moved axially toward disk 53 to grind both sides of the interposed ring. These disks are part of a grinding machine 35 the construction of which I have not deemed necessary to illustrate, other than to show a means for moving the disk 54 axially in timed relation with the ring feeding mechanism. The disk arbor 85 is carried by a 40 bracket 86 slidable on ways 87 and adapted to be reciprocated from the cam 88 by means of sectional levers 89-91 and a segmental gear 92 meshing with rack 93. A micrometer stop, not shown, limits the feed movement 45 of the disk 54.

The operation of my improvements is as follows:—During each revolution of the shaft 24 which is constantly driven in a clockwise direction, viewing Fig. 2, a ring 50 will be ground and ejected. The rings are stacked in the magazine and fed one at a time in the manner described above to the pre-loading station 23. The ring in the position shown in Fig. 2 is just one-half through 55 a complete cycle. The jaws have carried the ring between the grinding disks and are about to swing back away therefrom. This movement of the jaws is effected by downward movement of the links 26, which 60 simultaneously oscillates the bell-crank lever 27. This lever, after the jaw opening 64 has passed the loading station, withdraws the timer bar and its shoe 56, allowing the ring on said shoe to drop to the loading 65 station. Instantly after this action and

when the jaws have reached the dotted line position shown in Fig. 2, the ejector will in a quick vigorous action, eject the ring from the jaws which are now separated by the cam 46. When the link 26 moves upward 70 it will carry the jaws toward the disks, causing the ring at the loading station to enter the jaws and be clamped thereby, and causing the next ring to be fed to the pre-loading station. 75

It will be manifest from the foregoing that the various co-operating instrumentalities operate in timed relation to uniformly and accurately grind rings or any similar objects, and that in view of the automatic operation a relatively large number of rings 80 may be ground in a given period as compared with the grinding of rings by hand.

It is believed that the above conveys a clear understanding of the principles and 85 objects of my invention, and while I have illustrated and described but a single working embodiment thereof, it should be understood that various changes might be made in the construction and arrangement without 90 departing from the spirit and scope of the invention, as expressed in the appended claims, in which—

I claim:

1. In a ring grinding machine, the combination of a pair of abrasive disks for grinding the sides of a ring, and an oscillatory device for peripherally clamping a ring and feeding it between said disks by movement in one direction and for withdrawing the ring from the disks by movement in the opposite direction. 95

2. The combination with a pair of abrasive disks for grinding the sides of a ring, of a pair of oscillatory jaws shaped for peripherally clamping an interposed ring, and means for oscillating the jaws for carrying the ring between and away from said disks. 105

3. In a ring grinding machine, the combination of a pair of abrasive disks for grinding the sides of a ring, a pair of jaws each having a semi-circular jaw face whereby to peripherally clamp a ring, and means for swinging said jaws back and forth to carry a clamped ring edgewise between and 115 away from said disks.

4. In a machine for grinding piston rings, the combination of a pair of abrasive disks for grinding the sides of a piston ring, a pair of jaws shaped to conform to and 120 clamp a ring substantially throughout its periphery, means for moving said jaws back and forth to carry a clamped ring edgewise between and away from said disks, and means for axially ejecting the ground ring from the jaws. 125

5. In a ring grinding machine, the combination with a pair of abrasive disks, of a ring carrier of less width than a ring and constructed to hold the same with its 130

sides projecting, oscillatory means for moving said ring carrier into and out of space between the disks, and means for closing the disks to grind the opposite sides of the 5 ring while it is disposed between the disks.

6. In a ring grinding machine, the combination with a pair of abrasive disks, of a ring carrier of less width than a ring and 10 constructed to hold the same with its sides projecting, oscillatory means for moving said ring carrier into and out of space between the disks, means for closing the disks to grind the opposite sides of a ring while it is between the disks, and means for ejecting 15 a ground ring from the carrier after the ring leaves the disks and for delivering a new ring into the carrier.

7. In a ring grinding machine, the combination with a pair of abrasive disks, a 20 pair of jaws pivotally mounted and adapted for peripherally clamping an interposed ring, leaving the sides thereof projecting beyond the jaws, and means for moving the jaws about their pivot axis for carrying a 25 ring between and away from said disks.

8. In a machine for grinding piston rings, the combination of a pair of abrasive disks, oscillatory jaws shaped to peripherally clamp a piston ring, means for oscillating 30 said jaws to carry a clamped piston ring between said disks during movement of the jaws in one direction and to withdraw the ground ring during movement in the opposite direction, and means for axially ejecting 35 the ground ring from, and for axially inserting a new ring between said jaws during the interval of their movement away from and toward the disks.

9. In a machine of the character described, 40 the combination of jaws for peripherally gripping a ring and carrying it edge-wise between a pair of spaced abrasive disks, means for vertically supporting a ring in juxtaposition to the path of said 45 jaws, and means for moving said ring laterally between the jaws while the same move toward said disks.

10. In a ring grinding machine, the combination with a pair of spaced abrasive 50 disks, oscillatory means for carrying a ring edge-wise between and away from said disks, means for effecting a relative movement between the disks to grind the sides of an interposed ring, and means for laterally ejecting the ring from said first named 55 means after the ring is removed from between the disks.

11. In a machine for grinding piston 60 rings, the combination of means for grinding the sides of a piston ring, a pair of jaws shaped to peripherally clamp a piston ring and so mounted as to move back and forth to carry a clamped ring edge-wise between the grinding means and away there-

from, a magazine adapted for carrying a 65 stack of rings, means for removing a ring from the magazine and positioning it at a loading station in juxtaposition to the path of the jaws, and means for moving the ring laterally from said loading station into the 70 space between the jaws to be clamped thereby.

12. In a ring grinding machine, the combination with a pair of spaced abrasive disks, oscillatory jaws for carrying a ring 75 edgewise between said disks for grinding opposite sides of a ring, and mechanism for ejecting a ring from the jaws and inserting another there-between.

13. In a ring grinding machine, the combination with a pair of spaced abrasive disks, oscillatory jaws for carrying a ring 80 edgewise between said disks for grinding opposite sides of the ring, and mechanism for ejecting a ring from the jaws near the 85 end of their movement away from the disks and inserting another ring between the jaws during the approach thereof toward the disks.

14. In a machine of the character described, 90 the combination of a magazine carrying a stack of rings, means for feeding the rings one at a time to a loading station, a ring carrier having an opening for the reception of a ring, means for operating 95 said carrier to move a ring edgewise between opposed abrasive wheels, thence to a position at which the ring is ejected, and thence to one in which said opening is in alignment with the ring at said loading 100 station, and means for moving this ring into said opening in the ring carrier.

15. In a ring grinding machine, a pair of jaws concentrically mounted and each having substantially a semi-circular recess for 105 the reception of a ring, means for moving the jaws about their pivot axis to carry a ring edgewise between and away from a pair of abrasive wheels, and means for relatively moving said jaws about said axis to 110 release the ring and clamp a new one.

16. In a ring grinding machine a comparatively relatively flat jaw for clamping an interposed ring and carrying it between a pair of spaced abrasive wheels, one of said 115 jaws being relatively wide and constituting a guide against which the next ring to be ground is urged prior to its entrance between the jaws.

17. In a ring grinding machine a pair of 120 relatively flat jaws for clamping an interposed ring for carrying the same between a pair of spaced abrasive wheels, one of said 125 jaws being relatively wide, means for moving the jaws between and away from said wheels, means for ejecting the ground ring from the jaws during the interval away from the wheels, said wide jaw constituting

during this interval a guide against which is urged the next ring to be gripped between the jaws.

18. In a ring grinding machine, the combination of means for carrying a ring in a vertical plane edgewise between a pair of abrasive wheels and away therefrom, means for ejecting the ring laterally from the first mentioned means, and a rod on which said ejected rings are received.

19. In a ring grinding machine, the combination of a magazine adapted to carry a vertical stack of rings, means for removing from said stack the lowermost ring and placing it in a vertical position substantially in alignment with the opening between a pair of opposed abrasive wheels, and means for moving this ring edgewise between said wheels for grinding the opposite sides of the ring.

20. In a ring grinding machine, the combination of a magazine adapted to carry a stack of rings, a pair of abrasive wheels adapted for grinding the sides of a ring, jaws adapted to peripherally clamp a ring and to move past said loading station and between the abrasive wheels, and means for feeding a ring at said loading station axially between said jaws.

21. In a ring grinding machine, the combination of a magazine adapted to carry a vertical stack of rings, a slide upon which said stack rests and having an opening adapted to be positioned in alignment with the stack to receive the lowermost ring, means for moving said slide to remove said lowermost ring from the stack, means for conveying said removed ring to a loading station, a pair of abrasive wheels, and a carrier for taking the ring from the loading station and moving it edgewise between said

abrasive wheels to thereby grind the sides of the ring.

22. In a ring grinding machine of the character described, the combination of a vertical stack of rings, a reciprocable slide upon which said stack rests and having an opening adapted to be moved into alignment with the stack to receive the lowermost ring, means causing said slide to remove said lowermost ring from the stack, a pair of abrasive wheels, means for peripherally clamping a ring and moving it edgewise between said abrasive wheels, and means for causing a ring removed from said stack to be positioned in operative relation to said clamping means in which to be clamped by the latter.

23. In a ring grinding machine, the combination of a magazine for a stack of rings, a reciprocating member for removing from the stack the ring at one end thereof, means for grinding the sides of a ring, means for carrying said removed ring edgewise between the grinding means, and mechanism for operating said ring removing means, including a safety device for preventing feed of an end ring in the event of a ring jam.

24. In a ring grinding machine, the combination of a pair of abrasive disks, oscillatory jaws adapted to peripherally clamp a ring and to carry it edgewise between said disks by movement in one direction and withdraw it therefrom by movement in the opposite direction, means for ejecting the ground ring from the jaws approximately at their most remote position from the disks, and means for inserting a new ring between the jaws during their approach toward the disks.

VICTOR WINQUIST.
